Primary Examiner—Freda Nunn

CLAIM

The ornamental design for a side panel for a computer chassis, as shown and described.

DESCRIPTION

FIG. 1 is an elevation view of a side panel for a computer chassis showing my new design; the opposite side is not part of the claimed design.

FIG. 2 is a perspective view of the side panel of FIG. 1. FIG. 3 is a top plan view of the side panel of FIG. 1; and, FIG. 4 is a front elevation view of the side panel of FIG. 1. The features shown in broken lines are for illustrative purposes only and form no part of the invention.
